(57) **CLAIM**

The ornamental design for a safety plate for a harness as shown and described.

DESCRIPTION

FIG. 1 is a perspective view of a safety plate for a harness showing our new design, shown in a position of use with a front plate attached to a back plate;

FIG. 2 is a front elevation view thereof;

FIG. 3 is a rear elevation view thereof;

FIG. 4 is a bottom plan view thereof;

FIG. 5 is a top plan elevation thereof;

FIG. 6 is a right side elevation view thereof;

(Continued)

FIG. 7 is a left side elevation view thereof;
 FIG. 8 is an exploded perspective view thereof;
 FIG. 9 is an exploded bottom plan view thereof; and,
 FIG. 10 is an exploded right side elevation view thereof.
 The broken lines illustrate portions of the safety plate for a
 harness that form no part of the claimed design.
